Otis. Potter. Newton Massachusetts 8117X

Potter's Patent

The Schedule referred to in these Letters Patent and making part of the same containing a description in the words of the said Otis Potter himself of his Improvement in the construction of fliers of double spuders.

To all to whom these presents shall come. . Otis Potter of Newton in the County of Middlesex and Commonwealth of Massachusetts, Mechanic and Clocker. Be it known that the said Otis Potter have invented constructed and applied to all a new and useful improvement in the construction of fliers of double spuders.

My said Improvement consists in making all the parts of a flier of a single piece of malleable cast iron in the manner hereinafter described. The only way of making fliers for double spuders heretofore practiced with my knowledge is to make the arms of the arms ^{the bottom of wrought iron} the bottom of steel and the tubes of brass. The arms are joined with brass solder. The tubes are attached with brass solder & the bottoms are fastened by staking. Definitions of the parts of a common double spudder flier. Arm bearing at the top having a hole thro' the center for the passage of the screw. Arms parts which hold the tubes and extends to the bottom forming the top sides of the flier.

Bottom plate which connects the arms at the lower extremity having a hole in the center to admit the hub of the gear or pulley which gives motion. Tubes hollow grooves on the inner sides of the arms extending a little more than half way from the nose to the bottom.

My improved flier is constructed as follows. The part which forms the malleable cast iron. From thence the arms as far as the tubes extend are cast with a hollow groove on one side somewhat resembling the form of a key. This groove being partially closed from the side which the screw passes in the same manner as the tube is closed at the top by the joint of the arms with the bottom

the corners are turned or rounded to give additional strength and
stiffness. In the process of finishing the file one of the principal
operations to be performed is, that of straightening and forming into
proper shape to effect which a pair of heavy dies is provided, the up-
per and lower dies being exactly alike. The file is then heated and
while hot is laid into the upper die. When the upper die which
had previously been lifted up so as to reach high is allowed to fall
and by its momentum effects the object. It is hardly necessary to state
that the upper die moves upon guides rods.

Another important operation is, that of closing the tube which is also
effected by a pair of dies of a similar form. A tongue is made on the
upper die or rather the upper die consists of a tongue with a hollow
in its top. The part of the file which is intended to form the tube
is heated and laid therein. The upper die consists of an inverted
hollow groove the width of which is such as to come up to the
sides of the tube in its natural shape. In the centre of this groove
is a small tongue to prevent the edges of the tube from coming in contact.

The following is a sectional view of these dies and of the tube between
them. The upper die is allowed to fall and by its pressure against
the sides of the tube, causes the edges inward until they strike the tongue
in the centre which leaves them in the required shape. It is obvious
that this pair of dies must be circular at one end to comply with the
shape of the top of the file and that only one side of the file is op-
erated upon at once. The upper die runs upon guides rods and is allowed
to fall a sufficient distance to effect the object at a single blow.

The other operations of drilling, cutting, filing & polishing are common
to other purposed. What I claim as my invention and improvement
is, the application of the material together with the method of making
and finishing the file as above described. I declare my intent to have
and I have had, at my house the first day of March in the year
of one thousand eight hundred and thirty four
